UNITED STATES PATENT OFFICE.

GUIDO FORNACA, OF TURIN, ITALY.

VALVE MECHANISM FOR INTERNAL-COMBUSTION ENGINES.

Application filed March 20, 1926, Serial No. 96,229, and in Italy March 25, 1925.

This invention relates to an internal combustion engine having its valves grouped in sets and provides mechanism for simultaneously operating the valves of each set, characterized in that the operating cams for said valves are symmetrically disposed on both sides of a camshaft bearing so that the camshaft is not subjected to bending stress, said bearing having a guide for a cross-piece on which the cams act near the points of support of the valve stems and through which the valves are moved.

By this arrangement all flexure of the camshaft is eliminated and said shaft is subjected only to torsional stresses for which reason it can be made much lighter and intermediary supports can be omitted.

The cross-piece can also be very light and is therefore easily made by a stamping or pressing process.

Moreover, great precision in the operation of the mechanism is obtainable although the several parts do not require to be so very accurately constructed, thus realizing a great economy in manufacture, as well as facilitating the assemblage and replacement of the different members.

Slight displacement between the operating mechanism (camshaft, cross-piece, valve tappets) and the valve stems may take place without any inconvenience, as it is not essential that the camshaft axis and the axis of the valve stems be exactly in the same plane nor in absolutely parallel planes.

By way of example, one constructional form of the mechanism, applied to an engine having two camshafts, is illustrated on the accompanying drawing, whereon:

Fig. 1 is a cross section in the plane A—A of Fig. 3;

Fig. 2 is a longitudinal section in the plane B—B of Fig. 3; and

Fig. 3 is a plan.

Referring to the drawing, the upper part 1 of the cylinder head is fitted with guides 2 for the stems of the valves 3, and has integral shoulders 4, 14 to which are secured, by means of screws 8, the bearings 5, 5' supporting the camshafts 6 on each of which are cams 7 disposed in pairs, one on either side of a camshaft bearing.

Each bearing part 5 has an extension 9 serving as a guide for a cross-piece 10 formed with split ends in which adjustable valve tappets 11 are secured by means of screws 11'. The cross-piece has two surfaces 12, 12

engaged by the cams 7, 7 near the tappets 11 which are co-axial with the valve stems 3.

The shoulders 4, 14 form a box or casing for the valve mechanism and also guide the cross-piece between them, so that the latter cannot rotate. A cover 13, secured by means of screws, closes said box or casing and protects the entire valve mechanism.

During the rotation of the camshafts, each pair of cams 7, 7 depresses the corresponding cross-piece 10 on the extension 9 of the bearing part 5 thereby opening the valves 3, 3.

By this arrangement an abnormal stress 70 on the cross-piece 10 or its guide 9 is prevented, even if the parts are not very accurately constructed, because the extension 9 is centered only with relation to its own support.

The stress on the extension 9 is perfectly rational as, when there is a maximum stress, that is, when the valves begin to open, the cross-piece 10 is quite near the bearing support and therefore the bending moment is 80 very small.

The valve mechanism can be rapidly and easily dismounted and remounted and any required adjustment can be made at the valve tappets 11.

What I claim is:

1. A valve mechanism for internal combustion engines, comprising a plurality of valves grouped in sets and having stems in parallel relation, a cross-piece bearing on the end of the stem of each valve of a set, a shaft arranged above the cross-pieces, bearings for said shaft mounted between the valve stems of each set, and cams mounted on said shaft in proximity to and laterally of each bearing, each set of cams co-operating with a cross-piece for actuating the corresponding set of valves.

2. A valve mechanism for internal combustion engines, comprising a plurality of valves grouped in sets, and having stems in parallel relation, a cross-piece bearing on the end of the stem of each valve of a set, a shaft arranged above the cross-pieces, bearings for said shaft mounted between the valve stems of each set, a guide rod for each cross-piece carried by each bearing, and cams mounted on the shafts in proximity to and laterally of each bearing, each set of cams co-operating with a cross piece for actuating the corresponding set of valves.

3. A valve mechanism for internal com-

bustion engines, comprising a plurality of valves grouped in sets, and having stems in parallel relation, a cross-piece bearing on the end of the stem of each valve of a set, a shaft arranged above the cross-pieces, bearings for said shaft, mounted between the valve stems of each set, extensions formed on each bearing constituting guides for said cross pieces, and cams mounted on the shafts in proximity to and laterally of each bearing, each set of cams co-operating with a cross piece for actuating the corresponding set of valves.

4. A valve mechanism for internal combustion engines, comprising a plurality of valves arranged in pairs and having stems in parallel relation, a cross piece for each pair of valves for actuating the stems of the latter, a shaft extending above a plurality of cross-pieces, bearings for the shaft fixed between the valve stems of each pair of valves, a guide for the cross-pieces formed on and extending below each bearing, and cams mounted on said shaft in proximity to and laterally of each bearing in operative relation to a cross-piece whereby one of the latter will simultaneously actuate a pair of valves.

5. In a valve mechanism for internal combustion engines, the combination of cylinder

head, a plurality of valves in the latter grouped in sets and having stems in parallel relation, a cross-piece for each set of valves in operative relation to the valve stems, guide shoulders on said head to prevent rotation of the cross-pieces, a shaft arranged above the latter, bearings of the shaft fixed between the stems of each set of valves, and cams on said shaft in proximity to and laterally of each bearing and in operative relation to the cross-piece.

6. In a valve mechanism for internal combustion engines, the combination of cylinder head, a plurality of valves in the latter grouped in sets and having stems in parallel relation, a cross-piece for each set of valves in operative relation to the valve stems, guide shoulders on said head to prevent rotation of the cross-pieces, a shaft arranged above the latter, bearings for the shaft fixed between the stems of each set of valves, a hanging guide rod for each cross-piece formed on each bearing, and cams on the shaft on either side of the bearings in operative relation to the cross-piece of each set of valves.

In testimony that I claim the foregoing as my invention I have signed my name.

GUIDO FORNACA.
